UNITED STATES PATENT OFFICE.

JAMES DE BLASIO, OF DUNBAR, PENNSYLVANIA.

SAFETY QUICK-FIRE MINE.

Application filed July 11, 1923. Serial No. 650,905.

To all whom it may concern:

Be it known that I, JAMES DE BLASIO, citizen of the United States, residing at Dunbar, in the county of Fayette and State 5 of Pennsylvania, have invented certain new and useful Improvements in Safety Quick-Fire Mines, of which the following is a specification.

This invention relates to explosive mines 10 or blasting cartridges and more particularly to a novel improvement therein whereby the risks and hazards of storing or handling are reduced to a minimum.

Accordingly, a primary object of the invention is to provide a safety mine which is 15 susceptible of being quickly fired when properly emplaced for use and yet give a wide margin of safety to the user during the preliminary handling and after ignition of the 20 fuse.

Another and important object of the invention is to provide a mine or cartridge which is completely assembled and which is in readiness for instant use.

25 A further object is to provide a blasting cartridge which includes a metal holder for the explosive charge having a removable closure cap for facilitating loading of the holder with the explosive mixture, the said holder being provided with a waterproof covering to insure the contents against moisture and dampness. In connection with the metal holder it may also be pointed out that the detachable closure cap for the holder 30 carries therewith a safety fuse having one end in direct contact with the explosive mixture.

A still further object is to provide a cartridge including a holder and an elongated 40 fuse normally coiled thereabout in compact relation, and held in such relation by a fracturable band or collar while being handled and yet readily available for extension and emplacement upon breaking the holding 45 band by using the specially equipped free end as a handle. That is to say, the free end of the fuse is provided with a removable cover for protecting the same from dampness and which may be readily removed im- 50 mediately prior to the ignition thereof, but which before removal constitutes a handle for conveniently gripping the fuse to cause it to rupture the holding band or collar previously referred to.

55 With the above and other objects in view which will more readily appear as the nature

of the invention is better understood, the same consists in the novel construction, combination and arrangement of parts herein-after more fully described, illustrated and 60 claimed.

In the accompanying drawings:

Figure 1 is a side elevation showing one form of my invention in assembled relation.

Figure 2 is a longitudinal sectional view 65 taken on the line 2—2 of Figure 1.

Figure 3 is a cross sectional view taken on the line 3—3 of Figure 1.

Figure 4 is an enlarged longitudinal sectional view taken through the free end of 70 the fuse and the protecting device therefor.

Figure 5 is a side elevation of another form of my invention.

Figure 6 is a longitudinal sectional view 75 thereof, taken on the line 6—6 of Figure 5 and

Figure 7 is a cross sectional view taken on the line 7—7 of Figure 5.

Like reference numerals designate corresponding parts throughout the several figures of the drawings.

In both forms of my invention as shown in the accompanying drawings, I have provided a blasting cartridge which includes a tubular container 5 having a closed lower end 6 and an open upper end 7, the latter being closed by a cap 8 which has threaded engagement with the holder. The said holder is purposely made of metal of sufficient thickness and strength to withstand 80 crushing pressure and to prevent the charge or mixture from exploding caused by jar- 90 ring. As for the mixture itself it may consist of a suitable proportion of aluminum, potassium chlorate and sulphur, or a combination of potassium chlorate, black powdered antimony and sulphur, either of which have been found especially adapted to this type of cartridge.

In order to render the charge damp-proof, 100 I have provided the holder with a sealed covering 9 of water-proof paper.

In the form illustrated in Figures 1 to 4, I ignite the charge through the medium of a fuse 10 whereas in the form illustrated in Figures 5, 6 and 7 I ignite the charge through the medium of electrical conductor leads 11—11. The fuse 10 and leads 11 constitute elongated conductors. One end of the fuse 10 is passed through an opening 12 110 formed in the cap 8 and this end projects into the interior of the holder and has direct

contact with the explosive charge. This inner end of the fuse is held against outward movement by means of a pin 13 which passes through the fuse and is adapted to bear 5 against the end wall of the cap. The ends of the leads 11 extend through a slot 14 which extends downwardly from the upper edge of the holder and the ends of these leads are electrically connected with an explosive cap 15 which I have shown more or 10 less diagrammatically.

In each form the elongated conductor is coiled lengthwise around the holder, and this coil is held in its compact relation 15 against the holder by means of a fracturable band or collar 16 which I preferably form from paper, said collar extending transversely around the holder and consequently in a plane at right angles to the 20 general plane of the coiled conductor.

The outer or free end of the fuse 10 has inserted therein a primary ignition fuse 17, and this end of the fuse is normally covered and thereby protected against dampness by means of a covering 18 which is preferably formed of waterproof paper. A sleeve 19 preferably formed of heavy paper or cardboard is disposed between the covering 18 and the fuse and serves not only to 25 protect the end of the fuse 10 but also to protect the initial or primary fuse 17 from accidental harm. The outer end of the protector 18 is twisted as at 20 to form a seal for the protector.

30 From the foregoing, it will be observed that the cartridge is previously loaded so that the operator is not in danger by having to load the same. It will be noted that the holder and the elongated conductor for igniting the explosive charge are held in a very compact relation so that it will occupy but very little space and that the cartridge is ready for immediate use by the operator by simply taking hold of the covering 18 35 at the free end of the conductor and using it as a handle to sever the fracturable collar which holds the conductor in its coiled relation about the holder, thereby releasing the same for use.

The protector 18 is, of course, detached 50 after performing its service as a manipulating handle and in connection with the protector or hood 18 for the ignitable end of the fuse, it will, of course, be understood that after the protector has performed its 55 function as a manipulating handle for causing the fuse to rip or rupture the holding band or collar, it may be removed so as to expose the primary fuse 17.

Without further description it is thought 60 that the features and advantages of the invention will be readily apparent to those skilled in the art, and it will, of course, be understood that changes in the form, proportion and minor details of construction 65 may be resorted to, without departing from the spirit of the invention and scope of the appended claims.

I claim:

1. In a blasting cartridge, the combination with a holder for containing an explosive charge, of an elongated conductor connected with said holder for igniting said charge, said conductor being coiled around the holder, and a fracturable means embracing said coiled conductor for retaining the latter in compact relation to the holder.

2. In a blasting cartridge, the combination with a tubular holder for containing an explosive charge, of an elongated conductor connected with said holder for igniting said charge, said conductor being coiled longitudinally around the holder, and a fracturable means extending around the coiled conductor and holder.

3. In a blasting cartridge, the combination with a holder for containing an explosive charge, of a fuse connected with said holder for igniting said charge, and a protective cap mounted on the free end of said fuse, said protective cap being formed from waterproof paper.

In testimony whereof I hereunto affix my signature in the presence of two witnesses.

JAMES DE BLASIO.
